INVENTOR:

UNITED STATES PATENT OFFICE.

H. CLAY BASCOM, OF TROY, NEW YORK.

DESIGN FOR A PARLOR-STOVE.

SPECIFICATION forming part of Design No. 16,413, dated December 15, 1885.

Application filed November 10, 1885. Serial No. 183,051. Term of patent 7 years.

To all whom it may concern:

Be it known that I, H. CLAY BASCOM, a citizen of the United States, residing in the city of Troy, in the county of Rensselaer and State of New York, have invented and produced a new and original Design for Parlor-Stoves, of which the following is a specification, reference being had to the accompanying engraving of a stove having said design.

10 This design embraces several new, distinctive, and separate parts and combinations of parts which go to make up the whole design, as hereinafter specified, and shown in the foregoing engraving.

15 One part consists of the shape and ornamentation of the cover A, having a quadrilateral form, and the upwardly and inwardly inclined concavely-curved and tapering side a, and end b, with the upper lattice-work, c c', and lower compound floral and vine-form ornaments, d and d'.

20 Another part is the shape and ornamentation of the end door, B, embracing the inclined branch e, of combined floral and leaf ornaments.

25 Another separate and distinctive part of this design is the ornamentation of the rectangular pilasters C, embracing the long leaf ornament f, the base ornament g, the ornamental cap h, and the surface i.

30 Another distinctive separate part of this design is the shape and ornamentation of the door D, embracing the concavely-curved upwardly and rearwardly inclined upper portion, j, having the two pairs of light-openings k, of the form shown, with the molded top l and the convexly-curved lower portion, m, having the row of apertures n and intermediate ornaments, o.

35 40 The design for the front embraces the shape and ornamentation of the pilasters C, lower

door, D, upper door, E, and body-plate F, substantially as shown.

The design for the legs consists of the broad upper side parts, p, meeting at an angle, the 45 lower portion, q, and the compound floral ornament r.

The whole design embraces the shape and ornamentation of the cover A, end door, B, the front including the parts C, D, E, and F, the 50 base G, and the legs.

I claim as new—

1. In a design for a stove, the shape and ornamentation of the cover A, embracing the parts a, b, c c', and d d', as set forth. 55

2. In a design for a stove, the shape and ornamentation of the end door, B, embracing the compound ornament e, as shown.

3. In a design for a stove, the ornamentation of the rectangular pilasters C, embracing 60 the parts f, g, h, and i, shaped as shown and described.

4. In a design for a stove, the shape and ornamentation of the door D, embracing the parts j k l and m n o, as set forth. 65

5. In a design for a stove, the shape and ornamentation of the front, embracing the parts C, D, E, and F, as set forth.

6. In a design for a stove, the shape and ornamentation of the legs, consisting of the 70 parts p, q, and r, as set forth.

7. The design for a stove embracing the parts A B C D E F G and the legs, shaped and ornamented substantially as shown and described. 75

In testimony whereof I hereunto set my hand, in the presence of two subscribing witnesses, this 13th day of November, 1885.

H. CLAY BASCOM.

Witnesses:

MINA M. FONDA,

CHARLES H. BENEDICT.
